SHOE SEWING MACHINE

Alfred R. Morrill, Beverly, Mass., assignor to
United Shoe Machinery Corporation, Borough
of Flemington, N. J., a corporation of New
Jersey

Original application February 9, 1933, Serial No.
655,934. Divided and this application Novem-
ber 16, 1937, Serial No. 174,799

18 Claims. (Cl. 112—219)

This application is a division of Serial No.
655,934, filed February 9, 1933.

The present invention relates to shoe sewing
machines, and more particularly to hook needle
sewing machines such as are used for sewing
the uppers to the soles of turn shoes or the welts
and uppers to the insoles of welt shoes.

The objects of the invention are to simplify
and improve the construction and mode of op-
eration of the various parts of a shoe sewing
machine of this general type, whereby a greater
efficiency and certainty in operation of the ma-
chine are obtained, greater ease in starting is
secured, and provision is made, in the event of
15 breaking or mislooping of the needle thread for
automatically stopping the machine.

The invention is herein disclosed as embodied
in an automatic machine for sewing the welt
and upper to the insole of a welted shoe, in which
20 the shoe is supported on a jack and the jack is moved
with relation to the shoe operating de-
vices, and in which positioning and feeding
movements are imparted to the jack and shoe
supported thereon to cause the shoe to be pre-
25 sented properly to the operating means as the
point of operation is transferred about the shoe.
The machine hereinafter described as embody-
ing the several features of the present inven-
tion is the machine specifically set forth in ap-
30 plicant's co-pending application Serial No. 655,-
934 of which the present application is a division
which, as to the general construction and mode
of operation of its various parts is similar to the
automatic welt sewing machine disclosed in ap-
35 plicant's Patent No. 1,952,770, dated March 27,
1934, and in the patent to Topham and the pres-
ent applicant No. 1,616,714, dated February 8,
1927.

While the several features of the present in-
40 vention are set forth as embodied in an auto-
matic shoe machine, it will be understood that
the features are also capable of use in other
types of machines in which the shoe is held in
position by the operator. It is also to be under-
45 stood that except as defined in the claims, the
several features of the invention are not limited
to any particular construction or arrangement
of parts.

The several features of the invention consist
50 in devices, combinations and arrangement of
parts hereinafter described and claimed which,
together with the advantages to be obtained
thereby, will be readily understood by one skilled
in the art from the following description taken
55 in connection with the accompanying drawings

in which Fig. 1 is a view in front elevation of
an automatic lasting and welt sewing machine
embodying the several features of the present
invention; Fig. 2 is a front view, partly in sec-
tion, of the driving and stopping mechanism; 5
Fig. 3 is a view in left side elevation of a por-
tion of the machine head, the parts being shown
in stop position; Fig. 4 is a sectional plan view
of the machine head taken on the line 4—4 of
Fig. 3; Fig. 5 is a view of the machine head in 10
front elevation, the parts being shown in stop
position; Fig. 6 is a detail view, on an enlarged
scale in right side elevation, showing particu-
larly the needle, welt guide and welt cutter actu-
ating mechanisms; Fig. 7 is an enlarged detail 15
view of the needle segment and needle guide, as
shown in Fig. 6, but with the cover plate and
clamping screw for holding the needle segment
and needle guide in position removed; Fig. 8 is
a sectional view, taken on the line 8—8 of Fig. 20
7, with the cover plate and clamping screw in
position, as shown in Fig. 6; Fig. 9 is a detail
sectional view, taken on the line 9—9 of Fig. 6;
Fig. 10 is a detail sectional view, taken on the
line 10—10 of Fig. 6; Fig. 11 is a view illustrat- 25
ing the needle and thread finger actuating mech-
anisms, with the parts shown in the positions
assumed during the normal operation of the ma-
chine in sewing a seam; Fig. 12 is a detail sec-
tional view, taken on the line 12—12 of Fig. 11; 30
Fig. 13 is a view similar to Fig. 11 with the parts
shown in the position immediately upon throw-
ing the stop mechanism into operation; Fig. 14
is a detail sectional view taken on the line 14—14
of Fig. 13; Fig. 15 is a detail sectional view taken 35
on the line 15—15 of Fig. 13; Fig. 16 is a detail
view in left side elevation illustrating particu-
larly the thread finger and the thread cutting
and holding mechanism, the parts being shown
in stop position; Fig. 17 is a plan view of the 40
parts shown in Fig. 16; Fig. 18 is a view similar
to Fig. 16, the parts being shown in normal
sewing position; Fig. 19 is a plan view of Fig.
18, parts being broken away to show particularly
the positions of the thread finger and thread 45
gripper; Fig. 20 is a view similar to Figs. 16 and
18 with the parts shown in position during the
operation of the stop motion to stop the ma-
chine; Fig. 21 is a plan view of Fig. 20, the parts
being broken away to show the corresponding 50
positions of the thread finger and gripper; Fig.
22 is a view similar to Figs. 16, 18 and 20 after
the thread finger has been actuated to grip and
sever the thread; Fig. 23 is a plan view of Fig.
22, the parts being broken away to show the 55

corresponding positions of the thread finger and gripper; and Fig. 24 is a detail plan view of the feed carriage and the parts supported thereon.

The welt shoe sewing machine for sewing the welt to the upper and insole of a shoe while supported on a last herein disclosed as embodying in a preferred form the several features of the present invention, comprises a sewing head generally indicated at 50 within which the sewing and side lasting instrumentalities are housed, a shoe supporting jack comprising a toe support 52 and a heel support 54 pivotally secured thereto, a supporting base 56 within which is housed the supporting and actuating mechanisms for imparting the required feeding, turning and tipping movements to the jack, and a driving and stopping unit for the machine which is housed in a casing 58 on the base adjacent to the sewing head 50.

As has been stated, the general construction and mode of operation of the various parts of the illustrated machine are similar to the corresponding parts of the automatic welt sewing machine disclosed in applicant's Patent No. 1,952,770, and in the patent to Topham and the present applicant No. 1,616,714. The machine is completely automatic in operation, the shoe being supported on the jack during the sewing operation, and tipping and rotating movements being imparted to the jack in timed relation to the feed of the shoe so as to maintain the shoe at all times in the proper position with relation to the sewing instrumentalities. At the completion of the sewing operation, the driving mechanism for the cam shaft in the head of the machine and for the pattern cam shaft in the base from which the jack is actuated and controlled is thrown out of operation, and an auxiliary mechanism is thrown into operation which acts to perform certain additional operations including the completion of the rotation of the pattern cam shaft, the depression and outward movement of the jack away from the sewing instrumentalities, and the reverse rotation of the jack to its original position.

The shoe supporting jack comprising the toe support 52 and the heel support 54 pivotally secured thereto, is supported, actuated and controlled as in the machines of the patents above referred to. At its lower end the jack is mounted by a universal joint on the forward end of a horizontal arm or lever 590 which is pivotally mounted on a support 592 to move in a vertical plane, which support is pivotally mounted for movements in a substantially horizontal plane on a supporting member 594. The forked lower end of the member 594 carries trunnions 596 arranged to engage with corresponding bearings 598 in the machine frame. The movements of the several members of the jack are controlled through connections actuated by cams on the pattern cam shaft.

As in the machine of the patents above referred to, the devices of the present machine for operating upon a shoe comprise a curved hooked needle 60, a looper 62, a thread finger 64, a thread holder or gripper 66, a channel guide 68, and a welt guide 71. In addition to these devices, the present machine also is provided with a side lasting gripper comprising jaws indicated respectively at 72 and 74. Cooperating movements are imparted to these devices for operating on the shoe from a sewing cam shaft 76 (see Fig. 1) which is mounted to rotate on a horizontal axis in bearings in the sewing head 50, and is provided at one end with a spiral gear 78 arranged to mesh

with a corresponding spiral gear 80 which is formed integrally with a clutch sleeve 82 loosely mounted to turn on a vertical drive shaft 84 of the machine. The shaft 84 is continuously driven through reduction gearing from an electric motor mounted in the upper end of the casing 58.

The control mechanism for imparting positioning and feeding movements to the jack are arranged to impart a continuous feeding movement to the shoe past the stitch forming devices. To assist in the feeding of the work, the needle is mounted to reciprocate with the work in the line of feed. With the present construction, the needle 60 is mounted on a support or frame 86 (see Figs. 3, 4, 5 and 24) which extends rearwardly of the machine, and is sleeved to turn on a vertical pivot shaft 88. A rearwardly extending arm 90 formed on the hub of the support 86 carries a cam roll 92 which is arranged to engage in a peripheral cam groove in the cam disk 94 on the sewing shaft 76, so that a reciprocating movement is imparted to the support and the needle mounted thereon in the line of feed in timed relation to the sewing cycle.

As best shown in Figs. 6, 7, and 8, the needle 60 is rigidly clamped by means of a cover plate 98 and a clamping screw 100 to a needle segment 102 which is loosely sleeved to turn on a stud 104 formed on a plate 106 which is secured to the support 86. A groove 108 is formed in the periphery 30 on the needle segment to engage with a corresponding tongue 110 on the support 86.

The needle is supported by means of a needle guide 112 formed on a hub 114 which is loosely sleeved on the stud 104 and is held in position 35 thereon by means of a cover plate 116 and a clamping screw 118. The needle guide is positively moved towards and from the work through connections with the needle segment comprising a ball 120 mounted in a perforation extending 40 parallel with the axis of needle movement through a radial projection from the hub of the needle guide and arranged to engage alternately locking recesses 121 and 123 formed respectively 45 in the adjacent faces of the needle segment 102 and the cover plate 116. The forward movement 50 of the needle guide is limited by a fixed stop 124 projecting from the cover plate 116 into the path of a radially extending shoulder on the hub of the needle guide. When the guide is in this position, the recess in the hub of the needle guide is opposite the recess in the cover plate, while the needle segment continues its forward movement. The needle guide remains locked in position by the ball during the retracting stroke of the 55 needle segment until the recess in the needle segment comes opposite the recess in the hub of the needle guide. At this time a lug on the needle segment engages the radially projecting shoulder of the needle guide and during the continued 60 backward movement of the needle segment the needle guide is also moved backwardly, the ball 120 moving from the recess in the cover plate 116 to the recess in the needle segment, and locking the guide to the needle segment during the 65 continued backward movement of the needle segment and during the first portion of its forward movement. Oscillating movements are imparted to the segment 102 and needle 60 about the pivot 70 104 to advance and retract the needle through the work, by means of a cam lever 126 (see Figs. 3 and 6) pivoted on a rock shaft 128, and connected at its free end by means of a link 130 to the needle segment 102. A cam roll 132 on the cam lever 126 is arranged to engage with a needle

actuating cam groove 134 (see Fig. 6) formed in one face of the cam disk 94.

The present machine is provided with means for causing the needle to misloop during the last cycle of the machine upon stopping, so that no thread will be caught on the needle hook and drawn through the work as the needle is retracted to its normal stop position out of engagement with the work. With the present construction, the needle cam lever 126 is mounted on an eccentric pivot 136 (see Fig. 6) secured to the rock shaft 128, so that a rocking movement imparted to the rock shaft will vary the position of the pivot, and correspondingly vary the limit of the advancing movement of the needle through the work to prevent thread from being laid in the needle hook.

The shaft 128 is rocked to vary the needle throw upon stopping the machine through connections comprising a rock shaft 138 (see Fig. 2) arranged in line with a short shaft 140 mounted in the frame of the sewing mechanism above and slightly in front of the shaft 128. The stop mechanism of the machine illustrated more particularly in Fig. 2 is similar to that disclosed in the patent to Topham No. 1,791,176, dated February 3, 1931, the shaft 138 being a portion of the lock bolt carrier of the stop mechanism disclosed in said patent. The shaft 138 is connected to the short shaft 140 by inter-engaging slotted blocks, the arrangement being such that the rocking of the shaft 138 during the operation of the stop motion imparts a corresponding rocking movement to the shaft 140. The shaft 140 is provided with a rearwardly and downwardly extending arm having a gear segment meshing with a corresponding segment secured to the outer end of the shaft 128. During the operation of the stop mechanism, the shaft 140 is rocked in a clockwise direction and is then returned part-way to its original position. Through the connections above described a rocking movement first in a counterclockwise direction and then a partial return movement in a clockwise direction is imparted to the shaft 128. The eccentric 136 is thus shifted during the last stitch forming cycle to cause the forward movement of the needle to be shortened to such an extent that the thread is not laid in the needle hook during the operation of the looper, and the needle comes to rest out of engagement with the work with no thread in its hook.

The looper mechanism of the illustrated machine comprises the looper member 62 rigidly secured to the apex or tip of a triangular frame 156 (see Figs. 3 and 4), which at each of its two rear corners is connected by a universal joint to corresponding actuating cam levers 158. These levers 158 are mounted to turn on a pivot shaft 160, and are provided with cam rolls 162 arranged to engage respectively with cam grooves 164 formed in the outer faces of the cam disks 166 and 168 (see Figs. 3 and 4). The frame 156 at its forward end is supported yieldingly in sliding contact with a bearing surface 170 by means of two spring-pressed plungers 172 mounted in corresponding recesses in the machine frame, and arranged to engage with and exert an upward pressure respectively on the two arms of the frame 156 intermediate their lengths. The operation of the actuating cam levers 158 is timed to move the forward end of the sliding frame 156 and looper 62 in a circular path to impart the required encircling movements to the looper around the needle.

The thread finger 64 (see Figs. 3 to 5 inclusive, and 16 to 23 inclusive) comprises a lever arm mounted at its upper end on a pivot stud 174 to swing in a vertical plane, and is connected through a link 176 to the upper end of a lever arm 180 sleeved on a pivot stud 182. Formed on the hub of the lever 180 is a gear tooth segment 184 arranged to mesh with a corresponding gear segment 186 on one end of a rock shaft 188 journaled in a bearing 190 in the machine frame (see Fig. 12), and provided at its other end with an upwardly extending cam lever 192. A cam roll 194 carried on the lever 192 is arranged to engage a cam groove formed in one face of the cam disk 168.

Mechanism is provided which is arranged upon stopping the machine to impart to the thread finger 64 an abnormal movement to bring the thread finger into engagement with a thread gripper 66 to grip the thread, and thereafter through the continued movement of the thread finger, to cause a thread cutting knife to advance and sever the thread. The thread finger and gripper are then partially retracted to permit the return of the knife to inoperative position while the thread remains held between the gripper and thread finger preparatory to the beginning of a new stitching operation. The thread gripper 66 (see Figs. 3 and 16 to 23) comprises a lever arm which is pivotally mounted on the stud 174 to swing in a vertical plane, and is forced yieldingly toward the thread finger by means of a spring 196 attached at one end to the gripper lever, and at its other end to the machine frame. The movement of the gripper 66 about its pivot is limited by the engagement of the upper end of the lever with a fixed stop 198 on the machine frame. The thread cutting knife which cooperates with the thread finger and gripper to cut the thread is indicated at 200, and is formed on the lower end of an arcuate-shaped lever 202 (see Fig. 3) which is pivotally mounted intermediate its length to turn about a pivot 204 on the needle support 86, and at its upper end is provided with an offset nib 206 which extends into the path of movement of the gripper member 66. A tension spring 208 connected at one end to the arcuate-shaped lever 202 and at its other end to the needle support, tends to maintain the cutter in its retracted or inoperative position.

During the operation of the machine in sewing a seam, the thread finger, during each stitch forming cycle, engages the thread between the looper and the work, and draws aside a bight of thread as is usual in chain stitch inseam sewing machines. When the machine is stopped, the abnormal movement imparted to the thread finger brings the thread into contact with the gripper lever 66, and continued movement stretches a leg of the bight drawn out by the thread finger tightly between the end of the thread finger and the work. Upon actuation of the thread cutter lever 202 by the continued movement of the thread finger, and of the gripper lever 66, the cutting knife 200 engages the leg of the bight extending from the thread finger to the work and severs the thread, and upon the partial return movement of the thread finger the cutter lever 202 with the knife 200 is permitted to return to its original position while the end of the thread leading to the looper and to the supply is retained by the thread finger and gripper lever.

The construction above described constitutes a simple and efficient mechanism for controlling

the position and operation of a thread cutting knife which maintains the knife well out of the path of the shoe during the sewing and which causes the knife, when rendered operative, to advance into position to sever the thread with certainty in close proximity to the work. The construction also has the advantage that the parts which come in contact with the thread do not tend to collect wax from the thread and as a consequence become cemented together while the machine is idle and offer considerable resistance to movement when the machine is again started. With the construction above described, there is no necessity of thoroughly cleaning the parts before starting the machine in order to avoid breakage or injury as is the case with prior constructions. In the construction above described relatively small thread engaging and contacting surfaces are provided between the gripper and thread finger, and these surfaces have operative movement directly away from each other so that a relatively small amount of force is required to separate these surfaces in starting the machine, and danger of injury to the machine on account of the sticking together of these parts is eliminated.

In order to impart the required abnormal movements to the thread finger in stopping and in starting the machine to cut and grip the severed end of the thread, and to hold this end during the formation of the first stitch of the new operation, two separate cam grooves 210 and 212 (see Figs. 11 to 13 inclusive) are provided for the actuation of the thread finger cam lever 192, and a switch cam 214 which is similar in its general construction and mode of operation to that shown in the applicant's Patent No. 1,952,770. The switch cam 214, as in the application referred to, is arranged during the sewing operation to maintain the cam roll 194 in the inner cam path or groove 212. Upon stopping the machine, the cam lever 192 is moved positively to the left in timed relation to the rotation of the cam shaft 16 to swing the switch cam 214 about its pivot 216, and move the cam roll 194 into the outer groove or path 210. The mechanism through which this operation is carried out comprises a lever arm 218 loosely hung on the rock shaft 188, and connected through a link 220 with an arm 222 on the rock shaft 128. An abutment 224 on the lever arm 218 is arranged upon the rocking of the shaft 128 by the operation of the lock bolt carrier as above described in stopping the machine, to engage with an abutment 225 on the hub of the cam lever 192 to positively move the cam lever and roll 194 outwardly into the groove 210.

The thread take-up of the present machine, as best shown in Figs. 3 and 5, comprises a lever arm 226 which is pivoted on a shaft 228 on the machine frame, and is provided at its outer end with a guiding roll 230. The thread coming from the supply passes over a stationary roll 232, around a stationary roll 234, over the roll 230, and from there to the looper member 62. At its inner end the take-up lever 226 is provided with a cam roll 236 which is arranged to engage with a cam surface 238 formed in one face of the cam disk 94. A spring 240 coiled about the pivot shaft 228 and secured at one end to the take-up lever arm 226 tends to move the outer end of the take-up lever upwardly to tension the thread.

The shape of the cam surface 238 is such that the take-up is actuated positively to set the stitch and draw thread for the next stitch through the tension. At all other times the take-up is sup-

ported by the spring 240 and exerts a yielding tension on the thread during the action of the thread finger and looper in threading the needle and during the backward stroke of the needle in tightening the stitch. Overthrow of the take-up lever while being positively actuated to set the stitch and draw thread from the tension is prevented by the engagement of the roll 236 on the take-up lever with a raised portion of a cam surface 242 which is complementary to the cam surface 238 above referred to.

A novel and improved thread break stop is controlled by the take-up lever 226, and is rendered operative upon breaking of the thread to stop the machine. This mechanism comprises a vertically situated lever 244 (see Fig. 3) pivoted at 245 on the machine frame, and at its lower end arranged to engage with one arm of a lever 246 (see Fig. 4) which lever is one of a series through which motion of the lever 244 is transmitted to the lever 247 of the stop mechanism illustrated in Fig. 2. At its upper end the lever 244 has pivotally secured thereto, an arm 248 which intermediate its length carries a cam roll 250 arranged to engage a cam 252 on the cam shaft 16, and is arranged to extend into the path of a latch 254 formed on the rear end of the take-up lever 226. The arm 248 is pressed yieldingly to the right, as shown in Fig. 3, to maintain the roll 250 in engagement with the cam 252 by means of a compression spring 256 which is coiled about a rod 258 pivotally secured at its inner end to the arm 248 and at its outer end arranged to slide in a bearing 260. During the normal operation of the machine, the lever 244 will be maintained in the position shown in Fig. 3, and an idle oscillatory movement will be imparted to the arm 248 in timed relation to the rotation of the cam shaft 16 through the action of the spring 256 and rod 258. When the thread breaks during the operation of the machine, the take-up lever 226 is permitted to move about its pivot 228 by the pressure of the spring 240 to bring the cam roll 236 into engagement with the inner cam surface 242, so that as the roll moves onto the low portion of the cam, the latch 254 will fall behind the tip of the arm 248. With the continued rotation of the cam shaft 16, the roll 250 on the arm 248 will ride onto the high portion of its cam, causing the arm 248 to be turned about the latch 254 as a pivot, so that the lever 244 is moved about its pivot to throw the stop motion into operation.

Inasmuch as the take-up lever 226 is maintained in position against the pressure of the spring 240 only by the thread, it is desirable to provide means for preventing the engagement of the latch 254 with the thread stop mechanism in starting the machine, where for instance, the sewing operation is begun with a new length of thread which is not held in position by the thread gripper. For this purpose an abutment indicated at 262 in Fig. 3, is formed on the take-up lever 226, and is arranged to project into the path of a nub 264 on the thread finger actuating lever 192 while travelling in its outer groove 210. The movement of the thread finger cam lever 192 into its normal operating position under the influence of the switch cam 214 after the end of the first revolution of the cam shaft in starting the machine causes the nub 264 to move out of the path of the abutment 262 on the take-up lever 226.

To permit the cam shaft of the machine to be turned over by hand or the machine to be run, regardless of whether the machine is properly threaded or is without thread, means are

provided for locking the thread break stop permanently out of operation. As illustrated, this means comprises a manually operable lever 261 (see Figs. 3 and 4) pivotally mounted on the frame 5 of the machine and provided with a slot through which the outer end of the rod 258 passes. The lever 261 is interposed between the bearing 260 for the rod 258 and nuts 263 on the other end of the rod, and is provided with an inclined cam 10 surface 265, so arranged that a movement of the lever 261 upwardly from the position illustrated in Figs. 3 and 4 forces the rod 258 to the rear and withdraws the roll 250 from the cam 252.

The nature and scope of the present invention 15 having been indicated and a machine embodying the several features of the invention having been specifically described, what is claimed is:

1. A sewing machine having, in combination, 20 stitch forming devices including a hook needle, a looper, a thread finger pivoted for oscillatory movements to cooperate with the looper and needle in the formation of a stitch, a thread gripper member pivoted to cooperate with the finger to grip the thread, a thread cutting knife, and mechanism acting when rendered operative to impart an abnormal movement to the thread finger to engage the thread between the finger and the gripper member, and thereafter to render the knife operative to cut the thread.

30 2. A sewing machine having, in combination, stitch forming devices including a hook needle, a looper, a thread finger pivoted for oscillatory movements to cooperate with the looper and needle in the formation of a stitch, a thread gripper member pivoted to cooperate with the finger to grip the thread, a thread cutting knife, and mechanism rendered operative upon stopping the machine to impart an abnormal movement to the thread finger to engage the thread between 35 the finger and the gripper member, and thereafter to actuate the knife to sever the thread.

3. A sewing machine having, in combination, 40 stitch forming devices including a hook needle, a looper, a thread finger pivoted for oscillatory movements to cooperate with the looper and needle in the formation of a stitch, a thread gripper member pivoted to cooperate with the finger to grip the thread, a thread cutting knife, means acting normally to hold the knife in a retracted 45 position, and mechanism rendered operative upon stopping the machine to impart an abnormal movement to the thread finger to engage the thread between the finger and the gripper member and to advance the knife to sever the thread.

55 4. A sewing machine having, in combination, stitch forming devices including a hook needle, a looper, a thread finger pivoted for oscillatory movements to cooperate with the looper and needle in the formation of a stitch, a thread gripper member pivoted to cooperate with the finger, means tending yieldingly to advance the gripper member, a stop for positively limiting said movement of the gripper member to hold the gripper member normally out of the path of the finger, 60 and mechanism rendered operative upon stopping the machine to impart an abnormal movement to the thread finger to engage the thread between the finger and the gripper member.

5. A sewing machine having, in combination, 65 stitch forming devices including a hook needle, a looper, a thread finger pivoted for oscillatory movements to cooperate with the looper and needle in the formation of a stitch, a thread gripper member pivoted to cooperate with the finger to grip the thread, a thread cutting knife, a mov-

able support for the knife, and mechanism rendered operative upon stopping the machine to impart an abnormal movement to the thread finger to engage the thread between the finger and the gripper member, and through the continued 5 movement of the finger and gripper member to advance the knife support to sever the thread.

6. A sewing machine having, in combination, 10 stitch forming devices including a hook needle, a looper and a thread finger acting to draw aside a bight of thread between the work and the looper, a thread gripper member, a movable thread cutter, mechanism acting when rendered operative to impart an abnormal movement to the thread finger to grip the thread against the thread 15 gripper member, and means for moving the thread cutter to cut the leg of said bight extending from the thread finger to the work.

7. A sewing machine having, in combination, 20 stitch forming devices including a hook needle, a looper and a thread finger acting to draw aside a bight of thread between the work and the looper, a thread gripper member, mechanism acting when rendered operative to impart an abnormal movement to the thread finger to grip the thread against the thread gripper member, 25 a movable thread cutter arranged to cut the leg of said bight extending from the thread finger to the work, and means for advancing the thread cutter to cut the thread and to retract the thread 30 cutter while the thread remains gripped.

8. A sewing machine having, in combination, 35 stitch forming devices including a hook needle, a looper and a thread finger acting to draw aside a bight of thread between the work and the looper, a movable thread gripper member, mechanism acting when rendered operative to impart an abnormal movement to the thread finger to grip the thread against the thread gripping member and then move the gripping member, and a 40 movable thread cutter arranged to be actuated by the movement of said gripper member to cut the leg of said bight extending from the thread finger to the work.

9. A machine for operating on shoes having, in 45 combination, stitch forming devices including a hook needle, a looper, a take-up lever, a cam for actuating the take-up lever to set the stitch, spring means urging the take-up lever in a direction to exert a yielding tension on the thread 50 during each stitch forming cycle, a catch on the take-up lever, a trip member arranged upon movement of the take-up lever under the influence of said spring means upon breakage of the thread to be engaged by said catch, and mechanism rendered operative by the engagement of the catch with the trip member to stop the machine.

10. A machine for operating on shoes having, in combination, stitch forming devices including 60 a hook needle, a looper, a take-up lever, a cam for actuating the take-up lever to set the stitch, means cooperating with the cam to prevent overthrow of the lever while the stitch is being set, spring means urging the take-up lever in a direction to exert a yielding tension on the thread during each stitch forming cycle, a catch on the take-up lever, a trip member arranged upon movement of the take-up lever under the influence of said spring means upon breakage of the thread to be 65 engaged by said catch, and mechanism rendered operative by engagement of the catch with the trip member to stop the machine.

11. A machine for operating on shoes having, 70 in combination, stitch forming devices including 75

- a hook needle, a looper, a take-up lever, a cam for actuating the take-up lever to set the stitch, spring means urging the take-up lever in a direction to exert a yielding tension on the thread
- 5 during each stitch forming cycle, a catch on the take-up lever, a trip member arranged upon movement of the take-up lever under the influence of said spring means upon breakage of the thread to be engaged by said catch, mechanism
- 10 rendered operative by the engagement of the catch with the trip member to stop the machine, and means operative at the start of a seam for preventing engagement of the trip member by the catch.
- 15 12. A machine for operating on shoes having, in combination, stitch forming devices including a hook needle, a looper, a take-up lever, a cam for actuating the take-up lever to set the stitch, spring means urging the take-up lever in a direction to exert a yielding tension on the thread
- 20 during each stitch forming cycle, a catch on the take-up lever, a trip member arranged upon movement of the take-up lever under the influence of said spring means upon breakage of the thread to be engaged by said catch, mechanism rendered operative by the engagement of the catch with the trip member to stop the machine, and means operative at the start of a seam to prevent movement of the take-up lever sufficient
- 25 to cause the trip member to be engaged by the catch.
- 30 13. A machine for operating on shoes having, in combination, stitch forming devices including a hook needle, a looper, a take-up lever, a cam acting on the take-up lever for actuating the take-up lever positively to set the stitch, spring means urging the take-up lever in a direction to exert a yielding tension on the thread during each stitch forming cycle, and mechanism for
- 35 stopping the machine rendered operative by the movement of the take-up lever under the influence of said spring means upon breakage of the thread.
- 40 14. A machine for operating on shoes having in combination, stitch forming devices including a hook needle, a looper, a take-up lever, a cam for actuating the take-up lever to set the stitch, spring means urging the take-up lever in a direction to exert a yielding tension on the thread during each stitch forming cycle, mechanism for
- 45 stopping the machine rendered operative by the movement of the take-up lever under the influence of said spring means upon breakage of the thread, and means operative at the
- 50 start of the seam to prevent movement of the take-up lever under the influence of the said spring.
- 55 15. A machine for operating on shoes having, in combination, stitch forming devices including a hook needle, a looper, a take-up lever, a cam acting on the take-up lever for actuating the take-up lever positively to set the stitch, spring means urging the take-up lever in a direction to exert a yielding tension on the thread during each stitch forming cycle, mechanism for
- 60 stopping the machine, connections for throwing said stopping mechanism into operation rendered

operative by movement of the take-up lever under the influence of said spring means upon breakage of the thread, and means for locking said connections permanently out of operation.

16. A machine for operating on shoes having, in combination, stitch forming devices including a hook needle, a looper, a take-up lever, a cam for actuating the take-up lever to set the stitch, means cooperating with the cam to prevent overthrow of the take-up lever while the stitch is being set, spring means urging the take-up lever in a direction to exert a yielding tension on the thread during each stitch forming cycle, mechanism for stopping the machine, connections for throwing said stopping mechanism into operation rendered operative by movement of the take-up lever under the influence of said spring means upon breakage of the thread, said connections including a trip member, means for imparting an idling movement to said member in timed relation to the operation of the machine, and a catch associated with said take-up lever rendered operative by movement of the take-up lever upon breakage of the thread to engage with and vary the motion of said trip member to stop the machine.

17. A machine for operating on shoes having, in combination, stitch forming devices including a hook needle, a looper, a take-up lever, a cam for actuating the take-up lever to set the stitch, spring means urging the take-up lever in a direction to exert a yielding tension on the thread during each stitch forming cycle, a catch on the take-up lever, and a trip mechanism rendered operative to stop the machine upon breakage of the thread comprising an actuating lever, a trip lever mounted thereon arranged upon breaking of the thread to be engaged by said catch, a cam for oscillating the trip member in timed relation to the operation of the machine, and a cam roll on the trip member intermediate its length arranged upon engagement of the catch with the trip member to move the trip lever about the point of contact with the catch as a fulcrum to move the actuating lever to stop the machine.

18. An inseam shoe sewing machine having, in combination, stitch forming devices including a curved hook needle, a needle carrier mounted to oscillate to cause the needle to pierce and retract from the work, a needle guide mounted to oscillate on the same axis as the needle carrier at one side of the needle carrier, a stationary plate at the other side of the needle guide, a ball mounted in a perforation extending through the needle guide parallel to said axis, recesses in the needle carrier and plate to receive the ball and lock the needle guide alternately to the needle carrier and plate, and means for causing the ball to lock the needle guide to the plate during the latter portion of the work piercing stroke and first portion of the retracting stroke of the needle and to lock the needle guide to the needle carrier during the latter portion of the retracting stroke and first portion of the work piercing stroke of the needle.

ALFRED R. MORRILL.
